UNITED STATES PATENT OFFICE.

PEDER OLUF PEDERSEN, OF COPENHAGEN, DENMARK.

RELAY, MICROPHONE, OR OTHER SENSITIVE-CONTACT DEVICE.

1,122,799.

Specification of Letters Patent.

Patented Dec. 29, 1914.

Application filed May 28, 1912. Serial No. 700,289.

To all whom it may concern:

Be it known that I, PEDER OLUF PEDERSEN, a subject of the King of Denmark, residing at Copenhagen, Denmark, have invented 5 certain new and useful Improvements in Relays, Microphones, or other Sensitive-Contact Devices, of which the following is a full, clear, and exact description.

Through thorough practical experiments 10 it has been proved that an augmented sensitivity in relays, microphones or other sensitive contacts can be obtained by small mutual displacements of the electrodes, it being, however, provided that the said displacements take place in quite distinct manners.

One of the methods used is the following: 15 After the parts forming the sensitive contact in mechanical respect have assumed some position of equilibrium, one or more of the 20 electrodes or other parts forming the sensitive contact or parts of same are drawn a little away from the remainder of the parts 25 of which the sensitive contact consists. As an example of a construction according to 30 this principle the following may be named: In an ordinary carbon grain microphone the parts are arranged in such a manner that the diaphragm can assume two or eventually 35 more distinct positions relatively to the 40 grain box. One of these positions is the resting position of the microphone. In the same the pressure between the single parts 45 of contact is comparatively considerable, and the microphone is rather unsensitive. When 50 the microphone is to be used the diaphragm 55 is brought into the other position (or into one of the other positions). This latter position is called the working position of the 60 microphone. In this position the dia- 65 phragm is removed a small distance from the 70 grain box, compared to the resting position, and the grains in all essentials retaining the 75 same positions and situations as in the resting 80 position, the pressure between the dia- 85 phragm and the grains becomes smaller in the 90 working position than in the resting position, and this fact effects a great augmentation 95 of the sensitiveness of the microphone. From 100 this it appears that even if the microphone 105 does only obtain the great sensitiveness in the working position, the resting position is for the very attainment of the augmented sensitiveness at least just as important, the result being only obtainable 110 through the quite distinct coöperation be- 115 tween the two positions. The microphone re-

tains its augmented sensitiveness as long as the grains preserve their position from the resting position. If this position be disturbed through shakings or in any other 60 manner the microphone reassumes its normal sensitiveness. As this break down can only happen under influence of loud speaking it will often be appropriate to arrange the construction in a somewhat different 65 manner as indicated below.

In the above it has been essentially presumed that the microphone when not used was found in the condition of rest, and the working position arose from the fact that 70 the diaphragm was a little removed from the carbon box. However, it may also be arranged in such a manner that the microphone is normally in its working position and is only temporarily brought into its resting position. As regards attainment of the sensitiveness the effect will essentially be the same. By way of example the following way of executing the two modifications may be named: In the former case the diaphragm 80 can normally when the microphone is not used be pressed against the grain box by a spring; the working position is then produced by taking off the spring pressure. In latter case the resting position is produced 85 by the diaphragm being pressed against the grain box, while the diaphragm when the pressure is taken off spontaneously returns to the working position. Through the employment of such constructions applicant 90 has succeeded in getting microphones to speak 5-10 times louder than they do under ordinary circumstances. This is, however, not the only advantage of the new construction.

95 While an ordinary microphone can often "pack" and get into a very unsensitive condition, it will always be obtained when the new construction is used that the microphone becomes very sensitive when changing from 100 the resting position to the working position. Besides a better timbre is obtained.

The essential in the construction is, that the microphone has a resting position in which the acting parts are relatively near to each other, and a working position in which the parts are a little remote from each other compared to the resting position so that the augmented sensitiveness is produced by the microphone being brought from the resting- 105 to the working-position. The manner itself in which the positions and the transition

from one position to the other is produced is of secondary importance.

By way of example the following methods may be named. The necessary displacements can be effected in a magnetic way, the diaphragm being provided with a small iron armature acted upon by a magnet. The frame of the diaphragm can be bent or torn a little so as to slightly modify the shape of the diaphragm. A slight difference of pressure of air on both sides of the diaphragm can be effected. The diaphragm can be heated in such a manner that its shape is somewhat modified. It is likewise of secondary importance whether the establishing of a resting- and the working-positions and the transition from one to the other is effected by pressing directly buttons, keys, adjusting-levers, or the like, or whether the necessary adjustments are effected automatically by the telephone or the microphone being taken off the hook, by turning of the microphone, by closing or interrupting of certain electric circuits, or in other similar manners. Instead of one single working position it might be appropriate to have more, for instance of varying sensitiveness.

For sake of clearness displacement of the diaphragm has only been mentioned in the above; however, there is no objection to the displacement also being effected with other of the electrodes of the microphone or with other of the parts forming the sensitive contact. Likewise for sake of clearness only microphones are referred to; but the invention just as well relates to relays with microphonic contacts as well as to other sensitive contacts.

By way of example two constructions of microphones according to the invention are described and illustrated, Figure 1 showing one form in section and Figs. 2 and 3 another form respectively in section and front elevation.

1 designates the mouth piece of the microphone, 2 the diaphragm, 3 the grain chamber, 4 the rear carbon electrode, 5 a felt grain retaining ring, 6 a push button arranged on a flexible spring 7, which again carries a small projection 8. As long as the button 6 is in the position shown in Fig. 1, the entire microphone is in its normal position which here corresponds to the working position. In case the button remains unaltered in the shown position, the microphone acts quite as usual and with the normal sensitiveness. If the button 6 is pressed in, so that the shoulder 11 rests against the capsule 12, the projection 8 is at the same time pressed against the diaphragm 2 and this again against the grains in the chamber 3. In this position the microphone is rather unsensitive; but if the button 6 is again released, so that the parts

6, 7 and 8 re-assume the positions shown in Fig. 1, the diaphragm will return too and the pressure between the same and the grains and between the latter mutually will be much diminished and the sensitiveness 70 much augmented. The pressure on the button 6 can be exercised by the finger, as wanted by the person speaking, or automatically as indicated in Fig. 1 in which 9 and 10 indicate two positions of a rod. 75 When the telephone is not used and is thus hanging on the fork or hook, the rod occupies the position 9; as soon as the telephone is taken off the fork, it assumes the position 10. During the passage from the position 9 to 10 the button 6 is temporarily pressed in. When the telephone is replaced on the fork, the rod re-assumes the position 9.

Another modification is shown in Figs. 85 2 and 3. Here 13 indicates an iron ring fixed on the diaphragm, and 14 the pole shoes of an electro-magnet consisting of the iron frame 15 and the coils 16. The windings of the electromagnet are connected to the terminals 18 and 19, with which also the wires of the microphone are connected. When the microphone is without current, the pole shoes 14 only exercise a slight attraction on the ring 13, and the 95 microphone is in its resting position. As soon as the microphone is energized by current, the pole shoes 14 attract the ring 13, and the diaphragm enters into the working position. 17 is a protection casing.

Having now particularly described and ascertained the nature of my said invention and in what manner the same is to be performed, I declare that what I claim and desire to secure by Letters Patent of U. S. 105 A. is:—

1. A device of the character described, employing a finely divided variable resistance material as an essential element of the transmitting medium, and means for placing the particles of said material under additional pressure while the device is not being used and then relieving said additional pressure when the device is being used, in order to augment the sensitiveness 110 of said material.

2. In a device of the character described, the combination of a pair of electrodes, and means for placing said electrodes under additional pressure while the device is not 120 in use and then relieving the pressure while the device is being used to thereby increase the sensitiveness of said electrodes.

3. The method of augmenting the sensitiveness of a microphone or like instrument, 125 employing a finely divided variable resistance material as an essential part of the transmitting medium, which consists in compressing said material while the instrument is not being used for transmission 130

purposes to a point beyond that to which said material is compressed, while the instrument is being used, and then relieving this additional pressure on the material to permit the particles of the material to loosen and resume a condition in which they may be employed for transmitting purposes.

In witness whereof, I have subscribed my signature, in the presence of two witnesses.
